(57) **CLAIM**

The ornamental design for a leg pad for a hockey goalie or the like, as shown and described.

DESCRIPTION

FIG. 1 is a perspective view of a leg pad for hockey goalie or the like;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The portions shown in broken lines, including broken lines representing stitching, do not form any part of the claimed design.
